UNITED STATES PATENT OFFICE.

JASON J. PALMER, OF FLUSHING, NEW YORK.

STEAM-BOILER.

Specification of Letters Patent No. 16,693, dated February 24, 1857.

To all whom it may concern:

Be it known that I, JASON J. PALMER, of Flushing, Queens county, and State of New York, have invented a new and useful Improvement in the Mode of Constructing 5 Steam-Boilers; and I do hereby declare that the following is a full and exact description thereof, reference being had to the accompanying drawings and to the letters 10 of reference marked thereon.

Figure 1, is a perspective view of a boiler. Fig. 2, is a view of the interior or fire surface of the boiler, and a perspective of the 15 peculiar shaped flues. Fig. 3, is a sectional view of the boiler, crosswise, through the steam chest. Fig. 4, is a sectional view lengthwise.

The nature of my invention consists in so arranging the heating flues in the boiler, 20 that a superior and more rapid circulation of the water in the boiler shall be secured, and more particularly toward and in contact with the hottest parts of the boiler, or the sides and crown of the furnace or fire 25 shell.

The drawings represent a box-boiler, but the improvement can be easily adapted to any other form of boiler.

As will be seen, more particularly from 30 Figs. 2 and 3, the fire chamber A, occupies a central position in the boiler the sides of the boiler coming down upon each side, and the rear end, of the fire or furnace. From the position of the fire it will be evident that 35 the hottest part of the boiler will be that directly over the fire, and that in this portion the generation of steam will be the most rapid. Upon each side of the fire chamber A, and in either leg, so to speak, 40 of the boiler, I place a flue B b, spreading out in its lower part, and also extending up partially over the fire chamber. Fig. 3, shows the form of the entire water tank, and the position of these flues in it: and 45 these flues are also shown in Fig. 2. As will be seen these flues B b, are placed near the bottom of the boiler, and are much expanded at their lower parts, so as to enlarge their heating surfaces, and also for convenience 50 of cleaning and repairing. This expansion does not however interfere with any other part of the boiler, or with its convenient form or adaptability, as it is so located as to allow the corresponding expansion in the 55 boiler proper to be made in the vacant space underneath the furnace, where they also

have the benefit of the heat of the ashes and falling coal, and by which these expanded parts of the flues are kept continually hotter than they otherwise would be. As will be 60 also seen from Figs. 2 and 3, the flues B b, are not placed centrally in the sides of the boiler, or in the water tanks, but are so placed that between these flues and the inner or fire surface of the boiler, there is a much 65 less body or column of water, than there is between the flue and the outer side of the boiler. These flues extend upon each side of the boiler to the rear end, and also across the back end, and the heat and smoke, &c., 70 from the fire pass first into the flue at the rear end of the boiler, and then forward through the side flues and up the front end and over the top into the chimney C.

By this arrangement of flues, and being 75 placed close to the fire chamber, the less column of water receives the first heat of the fire, and then the heat through the return flues, and is therefore subjected to a greater heat than any other portion of the 80 water, by which it is kept in active motion and circulation, and thereby also keeps up or produces a constant circulation of the entire water which may be in the boiler, thus lessening danger from low water, since even 85 a small quantity of water will by this circulation be kept in contact with the hottest part of the boiler. This end is secured by the shape given the upper portion of the flues B b, turning up over the fire, and 90 which should cover about half, at least, of the arch D. By making the flues of this shape the water in a, is constantly brought or carried upon that part of the boiler D, directly over the fire, and naturally kept the 95 hottest, and where consequently steam will be generated the most rapidly. This arrangement and construction of flues therefore increases the capability or power of the boiler as a steam generator, and is ad- 100 vantageous under any circumstances, but particularly if the water in the boiler happens to get low, inasmuch as in that case the water will be constantly passing in contact with the hottest part of the boiler, from 105 which the most danger is to be apprehended. The heat of the furnace is further rendered more effectual by means of the perforated plates E, behind the furnace proper, and through which the flame, heat, &c., as to 110 pass before it enters the flue at the rear end of the boiler, the entrance to which is also

near the bottom of the boiler, and just above the level of the bottom of the ash hole under the grate. By the use of the plate E, the flame, &c., is prevented from passing into 5 the rear flue o, in a sheet or mass, but is separated and broken up, by means of the holes in E, and reflected and thrown in different directions, and thus made more effectual in generating steam. This effect is still 10 further increased by making the entrance o, to the flue below the plate E, and below the level of the fire; as the draft will be from the fire to the flue, consequently the upper part p, Fig. 4, of the fire chamber 15 will become a sort of reservoir of heat, continually rising from the fire, and not carried off with the draft, and therefore constantly acting with great effect upon the boiler and water above. As will be apparent 20 this construction secures a much more economical use of heat, than if the heat, &c., passed directly, on a level or nearly so, into the flue.

By the above construction and arrangement of boiler and flues, I also secure a 25 large extent of effective heating surface compared with the body of water, and therefore with a given amount or quantity of fire heat produce a much higher temperature of 30 steam in the boiler than is obtainable in other boilers.

As will be seen from Fig. 4, the flue at the rear end of the boiler is not represented with an enlarged chamber, and is not 35 usually so constructed, but it retains the extension and lap over the arch. The draft is governed by the damper f, and g, is a rod to drop or elevate the front part of the plate E.

40 In the case of small boilers the flues B,

may be placed toward or at the center of the water tanks, and in any case the size of the water space a, may be varied somewhat according to circumstances, the size and form of the boiler, &c.; but the principle 45 governing their position is, that they should be so placed that a great degree and extent of heat should act upon a comparatively small body of water for the more rapid generation of steam as above described. The 50 foot or leg of the boiler may extend a little below the flues to allow any sediment in the water to settle, and not be carried into the flues.

What I claim as my invention or improvement, and desire to secure by Letters Patent is—

1. The particular arrangement of the flues B b, B b, substantially as described, close to the fire shell of the boiler, and admitting 60 only a thin, but continuous, sheet of water between them and the fire shell, this thin sheet of water also connecting freely, at top and bottom, with the main body of water in the boiler—by which arrangement a more 65 rapid and complete circulation is produced, this thin sheet of water being constantly forced toward, and in contact with the sides and crown of the fire shell, i. e. the hottest parts of the boiler, and thus heated more 70 rapidly and made to circulate the faster.

2. I also claim the arrangement of the perforated plate E, it being interposed between the furnace and low exit into the smoke box or stack.

JASON J. PALMER.
